UNITED STATES PATENT OFFICE.

F. BARTON BROWN, OF BOSTON, MASSACHUSETTS.

UNDER-GARMENT.

SPECIFICATION forming part of Letters Patent No. 352,393, dated November 9, 1886.

Application filed March 1, 1886. Serial No. 193,586. (No model.)

To all whom it may concern:

Be it known that I, F. BARTON BROWN, of Boston, in the county of Suffolk and State of Massachusetts, have invented a new Improvement in Under-Garments; and I do hereby declare the following, when taken in connection with accompanying drawings and the letters of reference marked thereon, to be a full, clear, and exact description of the same, and which 10 said drawings constitute part of this specification, and represent, in—

Figure 1, a front view of the garment with the parts of the flap as secured at the front; Fig. 2, a rear view of the same; Fig. 3, a side 15 view of the same; Fig. 4, a rear view of the garment, showing the flap turned upward against the back and showing the opening through the legs at the rear.

This invention relates to an improvement in 20 what are commonly called "combination"-garments—that is to say, in which the body and legs are made together, designed for under-garments and bathing-suits, the object of the invention being to avoid the strain upon 25 the garment in bending forward, as in assuming a sitting position; and it consists in the construction as hereinafter described, and particularly recited in the claim.

A represents the body portion, and B B the 30 two legs. Above the waist the body with the sleeves may be in the usual form, and preferably so as to button in front, as indicated in Fig. 1. The legs are attached to the front portion of the garment, and form, respectively, 35 a continuation of each side of the front, open up to the waist-line, as indicated in broken lines; but instead of extending around so as to meet at the back, the leg portions at the waist are made narrower, so as to extend but little 40 to the rear of the hip-joint, as indicated at *a*, Fig. 3, and so that the rear portion below the waist is open, as seen in Fig. 4. Thus the leg portions in the rear are entirely detached from the body portion. To the lower edge of the 45 body portion at the back and about the waist-line, as seen in Fig. 4, a flap, C, is attached or formed as a part of the body, the flap being in length sufficient to pass down between the legs, so as to cover the opening at the rear, and 50 up in front. At each side of the flap C is an extension, D, in length sufficient to extend toward the front, as indicated in Figs. 1 and 3,

and at the extreme end the flap C is also provided with extensions E E to the right and left, so that when the flap C is drawn up between the legs to the front the two extensions E E may be joined to the extensions D D, as indicated in Fig. 1, thus securing the flap around the waist and between the legs, so as to completely cover the opening at the rear 55 and in the front, and as indicated in Figs. 1, 2, and 3.

The legs being attached to the front of the body at the waist-line, as seen in Fig. 3, and extended downward therefrom, as indicated 65 in broken lines, Fig. 3, inside the flap at the rear and entirely independent of the flap-connections, the movement of the body does not draw upon the legs at the rear, as in the usual construction, when the legs at the rear extend 70 up to the body. In the movement of the body, as in bending forward or in assuming a sitting position, the flap C moves with the body but slides upon the legs, and hence gives to the legs of the garment perfect freedom independent 75 of the body.

The flap C is cut into shape and gored, if necessary, as seen in Fig. 4, in order to bring it into the proper shape to pass between the legs without discomfort to the wearer. 80

By this construction the garment, while made as one continuous article, gives as much freedom to the wearer as if the parts were made separate from each other, and all strain upon the shoulders or garment in bending is 85 avoided.

I claim—

The herein-described combination-garment, consisting of the body A and the legs B B, permanently attached as a continuous garment, the leg portions extending from the front rearward at the waist-line to about the hip-line, open at the rear, with the flap C, attached to the back at the waist-line, adapted to be brought forward between the legs, and 90 provided with extensions D D and E E, the said extensions D D adapted to be brought forward at each side and to meet the extensions E E, so as to secure the said flap, substantially as described.

F. BARTON BROWN.
